Filed June 24, 1963, Ser. No. 290,050

5 Claims. (Cl. 340—11)

This invention relates to underwater transducers of the hollow cylindrical type vibrating in the radial mode, and the present application is a continuation-in-part of my application Serial No. 205,952 filed June 28, 1962.

An object of the invention is to improve the performance of transducers of this type as to band width and the ratio of the band width to the amount of active material.

Another object is to provide an efficient underwater transducer without the use of shielding or pressure release material.

Another object is to provide a highly efficient polarized magnetostriction transducer of this type in which permanent magnets supply the polarizing field.

Other more specific objects and features of the invention will appear from the description to follow.

Longitudinally continuous (sometimes herein referred to as closed) radially vibratile hollow cylindrical transducers are known. It is also known that in order to perform well, such transducers must not be too short, or the inside must be acoustically shielded from the outside to reduce interaction between the out-of-phase radiations from the inside and outside surfaces, respectively.

I have discovered that although, without auxiliary shielding, a certain overall length must be maintained for good performance, the amount of electromechanically-sensitive material required can be substantially reduced by employing a plurality of short, axially-spaced cylinder or ring elements instead of a continuous cylinder. It has been determined that the spacing between elements for good performance is between $.1\lambda_w$ and $.75\lambda_w$, where λ_w is the wavelength of sound in the ambient liquid medium, usually water. With a given amount of material, a plurality of spaced cylinder elements has the following advantages over a single, or closed, cylinder:

(a) It has a greater band width.
 (b) It has a greater efficiency in converting electrical power into sound, and vice versa.

(c) It enables a desired high radiation impedance with a smaller quantity of material, which with a power source of given magnitude results in a higher power intensity in the material, which is sometimes desirable. Thus, a high power level is required to efficiently drive an unpolarized magnetostriction transducer.

The following detailed description refers to the drawing, in which:

FIG. 1 is a longitudinal sectional view of a transducer incorporating the invention.

FIG. 2 is an end view of the transducer shown in FIG. 1.

FIGS. 3 to 5 are graphs showing impedance characteristics of transducers in accordance with the prior art and the present invention, respectively.

FIG. 1 shows a transducer 10 comprising four axially-spaced cylindrical transducer elements or rings 10a, 10b, 10c and 10d, all driven to expand and contract circumferentially with resultant radial vibration. The elements may be of any known type insofar as the acoustic advantages of axially-spaced rings are concerned. Thus they may be of the ceramic element type, as disclosed in my Patent No. 2,733,423 or of the magnetostrictive type. Magnetostrictive transducers are usually laminated, either by stacking flat annular laminations or winding

a long strip into a tight scroll. At the moment, we are concerned with the advantages of axially spacing radially vibratile rings or cylinders, regardless of their material or construction.

5 In order to radiate sound energy into a fluid medium, a vibrating source must experience a reaction from the medium, known as radiation impedance. Absolute values of radiation impedance for short cylinders are difficult to determine, but relative values are readily obtained from impedance curves such as shown in FIGS. 3 and 4. Both curves were derived from transducers consisting of magnetostrictive rings 6" in diameter and of rectangular cross-section, measuring .3" radially and $\frac{1}{2}$ " axially. These rings were stacked in groups of three, each group being enclosed by a winding and a neoprene housing. Such a group would not show efficient performance as a sound source, because the out-of-phase sonic pressures developed inside and outside would largely neutralize each other in the ambient medium. However, a close 10 assembly of four such groups defines a longer closed wall between inside and outside and becomes an efficient source. The impedance curve of such a four-group assembly having an overall length of 7" is shown in FIG. 3.

An unexpected performance, shown by the curve of 15 FIG. 4, is obtained from an assembly of four groups identical with the above groups by spacing the groups apart axially one-half wavelength (3.6" for the transducer dimensions cited) of sound in the ambient medium (.5 λ_w) at the resonant frequency. FIG. 4 indicates a 20 higher radiation impedance than FIG. 3 because the impedance varies less with change of frequency near the resonant frequency. Thus in FIG. 3, over a range of frequency of 1 kc. from 7.75 to 8.75 kc., the resistance varies from about 45 ohms to 72 ohms, or a range of 25 27 ohms, and the reactance varies between 204 ohms and 190 ohms, or a range of 14 ohms. In contrast, in FIG. 4 over substantially the same 1 kc. range from 7.5 to 8.5 the resistance varies between about 45 ohms and 57 ohms, or a range of 12 ohms, and the reactance varies between 30 40 about 175 ohms and 172 ohms, or a range of 3 ohms. Contrariwise, within resistance and reactance ranges of 4 ohms, the open construction of FIG. 4 permits a frequency range of about 1.5 kc. as against less than .25 kc. for the closed construction.

45 The use of spaced rings or cylinders adds another degree of freedom in the design of a transducer. Some illustrations of the advantages are as follows:

(1) For the example shown, without changing the 50 material used, an increase in band width for the sound source was achieved; also its output as a sound source per watt of input power was increased.

(2) One can obtain a given band width with approximately half the active material necessary in the closed construction.

55 (3) One can control the radiation impedance by spacing, while selecting the appropriate quantity of active material to make possible the solution of a problem in driving unpolarized magnetostrictive cylinders. The problem is that, without polarization, the active material can be efficiently driven only at a high power level. Therefore the power-handling capability of the active material must be matched to the electric power available.

Another example of the effect of proper spacing of 60 short cylindrical rings on efficiency and band width is 65 illustrated by FIG. 5, in which Curve A shows the output of a single ring and Curve B shows the output of four such rings. In each instance the length (in axial direction) of the individual rings is $.104\lambda_w$. The four rings of Curve B were spaced apart $.104\lambda_w$. It will be noted 70 from FIG. 5 that Curve A shows a band width of only about 450 cycles lying within a range of four decibels

whereas in Curve B the band width within the same range is about 2000 cycles.

The results of other tests are tabulated in the following table:

Item	No. of Rings	Axial Length Each Ring, λw	Axial Spacing Between Rings, λw	Output in db per Lb. of Material per Watt of Electrical Input	Q
(1) -----	8	.05	0	66.7	2.5
(2) -----	4	.1	.15	70.3	3
(3) -----	4	.05	.2	69	5
(4) -----	3	.1	.3	71.1	5
(5) -----	2	.1	-----	75.1	6
(6) -----	1	.1	-----	77.2	12
(7) -----	1	.05	-----	64	16
(8) -----	1	.1	-----	67.3	5

The one ring of Item (8) had a wall thickness (radial) of .3", three times that of the other rings which were .1". Comparing Item (8) with Item (4), both containing the same amount of material and having the same band width, the better performance of Item (4) is evident.

Comparison of Items (7) and (6) shows the very great advantage of the axially longer ring when used singly. Comparison of Items (7) and (3) shows the gain in using a plurality of spaced narrow rings over a single ring. However, Item (3) is still inferior to Item (2).

As a result of all my tests, it appears that an axial length of approximately $.1\lambda w$ gives optimum performance in terms of radiation efficiency both for single and multiple, spaced, rings, but it can be at least as low as $.05\lambda w$ and as great as $.15\lambda w$ without extreme reduction in radiation efficiency.

It appears that for the best radiation efficiency, the optimum spacing in multiple ring transducers can vary between $.1\lambda w$, and $.75\lambda w$.

The total length of multiple ring arrays may vary over a wide range depending only on the desired beam width of the radiation pattern.

From the data, it appears that a radial width of $.1\lambda w$ is optimum both for single and multiple spaced elements; and also that spaces between elements in an array should not be much below $.1\lambda w$ or much greater than $.5\lambda w$. Item (3) shows that, while not optimum, the use of $.05\lambda w$ width might be desirable at times where power output per pound is not the primary consideration and low weight is important.

A further advantage of the invention is that it provides a latitude of design to fit particular requirements. Thus as an example, a transducer having a resonant frequency of 350 cycles may be had with either of the following specifications:

(1) Single ring of:

Mean diameter -----	inches	134
Wall thickness -----	do	6.85
Length -----	do	23
Weight -----	lbs	20,800

(2) Two rings, spaced:

Overall length -----	inches	113
Mean diameter -----	do	103
Wall thickness -----	do	1.77
Length each -----	do	17.7
Total weight -----	lbs	6440

These two transducers, in spite of the disparity in weight, will perform identically except as to total power capacity.

A hollow cylindrical ring vibrating radially in water (the liquid medium in which devices in accordance with this invention are commonly employed) works against an impedance resulting from the mass reactance of, and

the radiation of energy into, the water. The mass reactance affects the frequency and band width of the resonance curve. The present invention enables the control of the relative values of the mass reactance and the radiation resistance by properly choosing the spacing between the rings and the overall length of the array of rings. The overall length is, of course, a function of the spacing and the ring dimensions.

It has been known that very short cylindrical rings vibrating radially in water show a mass reactance high with respect to the radiation resistance, and that such rings are inefficient converters of mechanical energy into acoustical energy.

The present invention greatly advances the art of transducer design in enabling the obtention of superior performance with the use of smaller amounts of active material and without the use of pressure release or other shielding material.

Where spaced magnetostrictive rings are used, as in the present invention, a highly desirable polarizing structure

utilizing permanent magnets becomes possible. This structure, as shown in FIG. 1, comprises a set of uniformly circumferentially spaced permanent magnets $12a$ and $12b$ between each adjacent pair of rings $10a$ and $10b$, $10b$ and $10c$, $10c$ and $10d$, respectively. Each set of magnets includes equal numbers of magnets $12a$ and $12b$, respectively, alternately spaced. The only difference between magnets $12a$ and $12b$ is that they are oppositely poled. In FIG. 1 all magnets $12a$ have their south poles uppermost, and all magnets $12b$ have their north poles uppermost. This produces a circumferential flux in each quadrant of each ring, the direction of which flux is opposite to that in adjacent rings. Thus the relative directions of the fluxes in different quadrants of the top ring in FIG. 1 are shown by the arrows in FIG. 2. In corresponding quadrants of each pair of adjacent rings, the direction of the polarizing flux from quadrant to quadrant, the directions of the winding 14 on each ring must also reverse from quadrant to quadrant, as shown in FIGS. 1 and 2, in order for the effects of the current in different quadrants to be in additive instead of subtractive relation to each other.

FIG. 1 shows a body 15 inserted in series with each magnet $12a$ or $12b$. These bodies are of high permeability material to keep the reluctance of the magnetic circuits low. In some instances the bodies 15 may be eliminated, and the permanent magnets 12 dimensioned to fill the gaps between adjacent rings 10 . However, many otherwise desirable permanent magnet materials have a very low permeability, and it is desirable to keep the permanent magnets as short as possible and fill the gap with a highly permeable material, such as powdered or laminated soft iron or one of the many alloys having even higher permeability.

Although for the purpose of explaining the invention a particular embodiment thereof has been shown and described, obvious modifications will occur to a person skilled in the art, and I do not desire to be limited to the exact details shown and described.

I claim:

1. A transducer for immersion in a liquid medium for translating sound waves in said medium into electrical waves in an electric circuit, and vice versa, comprising: a plurality of axially-aligned, spaced-apart, electro-mechanically-responsive, radially-vibratile rings and means electrically coupling said rings to said circuit for vibration in phase with each other; said transducer being open at the ends and between said rings whereby substantially all sides of each ring are in direct acoustic communication with a liquid in which said transducer is immersed.

2. Apparatus in accordance with claim 1 in which said rings are axially spaced apart less than $.75\lambda w$ where λw is the wavelength in said liquid medium at the opening frequency of said rings.

3. Apparatus in accordance with claim 2 in which said rings are axially spaced apart at least $.1\lambda_w$.
4. Apparatus in accordance with claim 1 in which the axial length of said rings is approximately $.1\lambda_w$ where λ_w is the wavelength in said liquid medium at the operating frequency of said rings.
5. Apparatus according to claim 4 in which said axial spacing exceeds the axial length of said rings.
